United States Patent Office.

ABRAM C. STANNARD, OF ROCK COUNTY, WISCONSIN.

Letters Patent No. 65,960, dated June 18, 1867.

IMPROVED WASHING MACHINE.

The Schedule referred to in these Letters Patent and making part of the same.

TO WHOM IT MAY CONCERN:

Be it known that I, ABRAM C. STANNARD, of Rock county, and State of Wisconsin, have invented a new useful improvement in a Washing Machine; and I do hereby declare that the following is a full, clear, and exact description thereof, reference being had to the annexed drawing, making part of this specification, the same letters of reference indicating the same parts in each figure.

The nature of my invention consists in a framework that can be raised and lowered and kept in place by means of eccentrics having straight-edged surfaces, and made with several sides, as in a square, hexagonal, octagonal, or other form, having several straight sides, to form a rest to suspend the framework at any desired height. Also, in a frame, within the first-mentioned framework, that has attached to its lower end a convex wash-board, provided with perforations to allow water to escape, and prevent adhesion of the cloths to the board. Also, in providing the last-mentioned framework with two independent springs, of a peculiar construction, and used to allow a yielding motion when cloths of more thickness accumulate on one side, between the board and rollers below, than on the other side, to preserve the efficiency of the machine and prevent injury to the clothes. Also, in a projection of one end of the box that contains the washing mechanism, which serves the double purpose of furnishing a convenience for attaching a clothes-wringer, and, when the washing mechanism is removed, forms a convenient sink for domestic purposes.

Figure 1 is an elevation of my machine.

Figure 2 is a top view, showing work inside the washing-box, also showing the perforation in the washing-board.

Figure 3 is a view longitudinally through the centre of my machine, with a part of the washing mechanism inside the washing-box.

Figure 4 is a sectional view of the rollers and sides of my washing-box, showing the grooves in the side of the box, to allow the framework and mechanism to be raised and lowered vertically.

Figure 5 is a sectional view, at right angles with figs. 1 and 3.

A and B are the sides of the washing-box that contain the washing or operating mechanism. They have grooves to receive the upright I I of the framework; also the washing-box stands on legs H, and has a projection, E, from F to C, the part E serving as a shelf in a sink, into which the washing-box is converted by removing the washing mechanism used in washing, the projection serving also the important purpose of having attached to its extreme end, at C, a wringer—overcoming the great difficulty of a wringer being in the way when the box is made without the projection. To the lower end of the uprights I I, on their inside, are attached the longitudinal pieces R, connected together by girths X. In the pieces R the rollers S revolve. Inside the uprights I is the swinging mechanism, composed of parts M, P, L, K, and U. On the under edge of P is attached the fluted or corrugated convex wash-board Q, which is provided with perforations i i i i, which allow air and water to escape from under the wash-board, which prevents the clothes from clinging to the wash-board, and also allow water to pass freely to the lower side of the wash-board as it is raised repeatedly and rapidly in the process of washing. Between the rollers S and the wash-board Q are placed the clothes to be washed, the springs Y and Y' yielding, to allow a large or small quantity of clothes to be washed at a time. The springs may be made of rubber tubes, as Y', or a spiral spring, as Y. The eccentrics J may have a knob, a, to aid in moving them—the dotted lines in fig. 1 show them in different positions—and may rest on the top edges of the box, on any one of their sides; thus, if the side nearest the pivot rests on the upper edge of the box, the frame of the working mechanism will be at its lowest point in the box, and when the side of the eccentric farthest from the pivot rests on the edge of the box, the framework is at its highest point of suspension in the box, and it will readily be perceived that the height of suspension depends on which of the several sides or edges of the eccentrics rests on the edge of the box; and this adjustability is important in that the washing mechanism can be adjusted in the box, as to height, to correspond with the amount of clothes and quantity of water necessary to be used in a given washing. Round eccentrics, by the motion of the machine in washing, fail to retain their position, and gradually revolve until the working mechanism reaches its lowest point, but when the eccentrics present straight sides or edges, to rest on the edges of the box, the working mechanism retains the position in which it is placed. This certainty of retaining the height or position desired

I deem very important. The perforations *i. e.*, &c., in the wash-board Q are important, in allowing air and water to escape, in preventing a cohesion or clinging of the clothes to the wash-board, and in furnishing ingress for water to the under side of the wash-board in the process of washing, and also prevents splashing of the water. I will also state that I do not confine myself to any particular number of perforations in the wash-board. I am aware that round eccentrics have been used to support the working mechanism inside a washing machine box, and I do not claim broadly eccentrics in a washing machine. I refer particularly to the patent of A. B. Clark, dated October 17, 1865.

What I claim as my invention, and desire to secure by Letters Patent, is—

1. Straight-edged-eccentrics J and J, when made substantially as described, and used to hold the working mechanism I, P, and K of a washing machine to any desired altitude within the washing-machine box A, and the whole combined and operated substantially as and for the purposes described.

2. The general arrangement of box A, rollers S, arranged in frame R; wash-board Q, and operating framework M, P, J and K, and U, kept to any desired altitude, by means of the straight-edged eccentrics J and J, when the whole are constructed, arranged, and operated substantially as and for the purposes described.

ABRAM C. STANNARD.
